His Attorney.

UNITED STATES PATENT OFFICE.

FRANK C. DE REAMER, OF SCHENECTADY, NEW YORK, ASSIGNOR TO GENERAL ELECTRIC COMPANY, A CORPORATION OF NEW YORK.

ELECTRIC VACUUM-CLEANER.

1,282,548.

Specification of Letters Patent. Patented Oct. 22, 1918.

Application filed January 31, 1918. Serial No. 214,575.

To all whom it may concern:

Be it known that I, FRANK C. DE REAMER, a citizen of the United States, residing at Schenectady, in the county of Schenectady, State of New York, have invented certain new and useful Improvements in Electric Vacuum-Cleaners, of which the following is a specification.

The present invention relates to electric vacuum cleaners of the type comprising a casing mounted on rollers and housing a motor and fan, the casing being provided with a handle by which it is pushed over the surface to be cleaned.

The object of my invention is to provide an improved arrangement of electric switch and operating means therefor for closing and opening the motor circuit of the cleaner, and for a consideration of what I believe to be novel and my invention, attention is directed to the accompanying specification and the claims appended thereto.

In the drawing, Figure 1 is a side elevation of a vacuum cleaner embodying my invention, and Fig. 2 is a bottom plan view thereof.

Referring to the drawing, 5 indicates the fan chamber of the cleaner casing, 6 the nozzle, 7 the motor, 8 the dust bag and 9 the handle which is pivoted on the casing of motor 7 and is used to propel the cleaner over the surface to be cleaned. In the present instance the cleaner is shown as being of the type in which the motor is horizontal and it is supported on two rollers 10, one at each end of the nozzle 6, and a roller 11 carried by a frame 12 at the rear central portion of the motor 7. Only one roller 10 shows in the drawing, but it will be obvious that the other is similarly arranged at the other end of the nozzle. The above described structure may be taken as typical of electric vacuum cleaners, and as its detail structure forms no part of the present invention, further description is unnecessary.

Now, according to my invention, I provide an electric switch of the push type, that is, of the type which has two buttons, the switch being closed by pushing one button and opened by pushing the other button, and I fasten this switch to the motor casing at a point directly beneath it. I then provide an actuator for the switch which projects out to the rear of the cleaner casing

and is particularly adapted to be actuated by the foot of the operator. The switch is indicated at 13 and it may have any suitable internal structure, the essential thing being that it has two buttons, one which is pushed to close the switch and the other to open the switch. The buttons are indicated at 14 and 15, and are attached to a push bar 16 which moves back and forth to close and open the switch. The switch casing is provided with two projecting parts 17 which receive screws 18 by which the switch is fastened to the motor casing and the ears 17 are suitably curved to fit the contour of such casing. The actuator for the switch comprises a lever 19 pivoted to the motor casing at 20 just to the rear of the switch 13. One end of lever 19 is provided with a fork 21, the two arms of which terminate adjacent the buttons 14 and 15, and are provided with ears 22 which engage the buttons. The other end of lever 19 projects through an opening 23 in frame 12 and terminates just above the rear roller 11 to form a piece 24 adapted to be engaged by the foot of the operator to close and open the switch. The piece 24 projects sufficiently far to be readily accessible and is preferably provided on opposite sides with a covering of rubber or other suitable material, as indicated at 25, which acts as a wear piece and also gives a better frictional engagement with the leather of a shoe than would metal, thus assisting in operating the switch. If desired, the material 25 may be red on one side and black on the other, or have other distinguishing colors to indicate which side of the lever to press to close or open the switch. To operate the switch 13 it is only necessary to push the lever 19 back and forth with the foot. This operation is aided by the end of the lever being located directly over the frame 12 which carries roller 11 as the toe of the operator is guided by and be balanced on the top of frame 12.

With the above described arrangement it will be seen that the switch is placed at a point where it is protected from possible injury and where it does not break into the contour of the motor casing and affect unfavorably its appearance. At the same time it permits of a very cheap and rugged form of switch being used, and one which is readily adapted to be operated by a simple lever pivoted adjacent it. Furthermore, the

2
operating end 24 of the lever, while it is readily accessible to the operator's foot and handy to actuate, is located at a point where it is not likely to be moved accidentally or 5 be bumped while the cleaner is being used with possible injury to it or the switch.

In accordance with the provisions of the patent statutes, I have described the principle of operation of my invention, together 10 with the apparatus which I now consider to represent the best embodiment thereof; but I desire to have it understood that the apparatus shown is only illustrative, and that the invention can be carried out by other 15 means.

What I claim as new and desire to secure by Letters Patent of the United States, is:—

1. The combination with a vacuum cleaner having an electric motor for operating it and 20 a casing for the motor, of a switch for controlling the motor circuit mounted on the motor casing directly beneath the motor, and an operating lever for the switch pivoted adjacent the switch and projecting to 25 the rear of the motor casing whereby it is adapted to be operated by the foot of the operator.

2. The combination with a vacuum cleaner having an electric motor for operating it and a casing for the motor, of a push switch 30 of the two-button type for controlling the motor mounted on the motor casing directly beneath the motor, and an operating lever for the switch pivoted adjacent thereto, said lever having a fork at one end, the two arms 35 of which engage the buttons of the switch, the other end of the lever projecting to the rear of the motor casing whereby it is adapted to be operated by the foot of the operator.

3. In a vacuum cleaner having a horizontally extending motor provided with a casing, and a supporting roller to the rear of the casing, the combination of a push 40 switch located beneath the motor casing, a 45 lever pivoted adjacent the switch and provided at one end with operating means for the switch, the other end of the lever projecting to the rear of the motor casing to a point above the roller.

In witness whereof, I have hereunto set my hand this 26th day of January, 1918.

FRANK C. DE REAMER.
